TUFTED FABRICS WITH TAPED EDGES AND METHOD OF MAKING THE SAME

William Ebersold, Norristown, Pa., assignor to James Lees and Sons Company, Bridgeport, Pa., a corporation of Pennsylvania

Application April 3, 1953, Serial No. 346,739

6 Claims. (Cl. 2—278)

This invention relates to rugs, carpets or the like and more particularly to rugs, carpets or the like of the tufted type.

The principal object of the invention is to provide a rug of the tufted type wherein the side edges are substantially straight and parallel to one another.

A further object of the invention is to provide a machine for making rugs of the tufted type which will produce rugs with side edges that are substantially straight and parallel to one another.

A still further object of the invention is to devise a method for making rugs of the tufted type, having side edges that are substantially straight and parallel to one another.

The fabric backing used in making tufted type rugs frequently is received from the manufacturer with undulating selvage edges. Consequently, it is difficult to obtain a finished product with exactly parallel edges. Furthermore, the edges of the fabric tend to shift laterally of the needles during the tufting operation with the result that the tufting yarn becomes clogged and snarled, because the needles having no backing to pierce form successive unsecured loops on their under side of the fabric backing. The only solution to this problem known prior to the present invention has been to adjust the position of the backing roll with respect to the tufting machine, so that variations in width of the fabric backing can be compensated for by moving the backing beneath the needles, as necessary. The disadvantage of this method is that frequently substantial quantities of the fabric backing are fed into the tufting machine before the backing roll can be adjusted.

This invention contemplates the provision of compensating means on the tufting machine to assure a product having exactly parallel edges. The machine used in the present invention is fully described in applicant's copending application Serial No. 346,740, filed April 3, 1953. Reference is made to that application for details of the tufting machine.

A more particular object of the invention is to provide tape means for each edge of the fabric backing, the tape means being secured by tufting to the backing in such a manner that parallel edges result.

These and other objects of the invention and the various features and details of construction and operation thereof are more fully set forth hereinafter with reference to the accompanying drawings in which:

Fig. 1 is a plan view of the present invention modified in part to disclose certain of the elements more clearly;

Fig. 2 is a view taken substantially on line 2—2 of Fig. 1;

Fig. 3 is a view taken substantially on line 3—3 of Fig. 1;

Fig. 4 is a view taken substantially on line 4—4 of Fig. 1, and

Fig. 5 is a view of a modified form of the invention.

With reference to the drawings the machine for making rugs of the tufted type therein illustrated comprises a

2

spreader roller 1, a pin roller 2, tape folding horns 3 and tape adjusting means 4. All of these elements are collocated to effect a result that will be apparent hereinafter. The details of the tufting operation are disclosed in applicant's above identified copending application.

The backing fabric 5 is fed from a roll, not shown, by the action of the power actuated pin roller 2. Interposed between the roll and the pin roller 2 is a spreader roller 1 which has outwardly directed helical indentations in the surface thereof to stretch the fabric backing laterally towards each marginal edge. Tapes 6 are fed from suitably mounted rolls, not shown, in a direction perpendicular to the direction of feed of the fabric backing. Adjacent each marginal edge of the fabric backing 5 is mounted a horn 3 which engages the tapes and changes their direction of travel so that they are then fed substantially parallel to the fabric backing.

The adjusting means 4 are constructed and arranged to receive the tapes 6, to fold them double, and to maintain them in spaced parallel relation. It will be understood that the folded tapes envelop the undulating marginal edges of the fabric backing so that the variations in width of the backing are concealed within the parallel tapes. After the tapes engage the adjusting means the fabric backing together with the tapes are fed into engagement with tufting needles, not shown, so that the entire width of the backing fabric including the tapes is tufted and no other means is necessary to secure the tapes to the backing.

The particular construction of the adjusting means is shown in Fig. 3 wherein a bar 7, adjustably secured at one end by any suitable means, such as by slot and bolt, extends laterally towards a marginal edge of the backing fabric and is provided at its other end with a clip, generally designated by reference numeral 8 and comprising spaced parallel legs 9 and 10 respectively and an intermediate leg 11 joined to the leg 9 along one edge thereof by the curved portion 12. A similar curved portion joins the opposite edge of leg 9 to a corresponding edge of leg 10.

It will be apparent that the outermost edge of the leg 11 engages the tape 6 and cooperates with the legs 9 and 10 to fold the tape double. The marginal edges of the fabric backing 5 are received within the fold thus formed and the fabric backing along with the tapes is fed into the tufting machine. The distance between the legs 11 of the respective opposed adjusting means remains constant while variations in the width of the fabric backing are concealed in the fold.

A modification of the invention is disclosed in Fig. 5 in which unfolded tapes 13 are arranged with respect to the marginal edges of the fabric backing so that the finished product has parallel side edges. It will be noted that the rug of Fig. 5 can readily be made by feeding the tapes from overhead rollers, not shown, so that they are fed between legs 9 and 11 of the adjusting means.

Since the distance between the curved portions 12 of the respective opposed adjusting means remains as predetermined, the tapes of the finished rug will be parallel.

A latex coating 16 is then applied to the entire under side of the rug thus formed to secure the tufts in place and to eliminate slippage when the rug is used.

I claim:

1. A tufted pile fabric comprising a backing having side edges, a tape overlying said edges, and a series of pile yarns, said pile yarns lying flush in parallel relation against the face of said backing and said tape longitudinally thereof and projecting through said backing and tape at spaced intervals along the length thereof to form pile projections on the opposite faces of said backing and tape, the outermost free edges of said tapes being in parallel relation to said pile yarns, the outermost pile yarns of said series projecting through said tape at spaced

3

intervals along its length to form pile projections on the opposite face thereof and secure the tape to said backing, said projections being in lateral alignment with the projections of the remaining pile yarns of said series.

2. A fabric according to claim 1 wherein said tapes are folded over upon themselves to embrace said side edges of the backing, the folded edges of the tape being the free edges thereof paralleling the pile yarns.

3. A method for making tufted pile fabrics from backing having undulating edges comprising the steps of laterally tensioning the backing, applying a tape along each of said undulating side edges in overlapping relation thereto with the outermost free edges of said tapes in spaced parallel relation, arranging a series of parallel longitudinal pile yarns on one face of said backing parallel to said free edges of the tape, and projecting simultaneously portions of each pile yarn through said backing and said tapes across the entire width of the fabric including said tapes to secure the latter in place.

4. In a method for making tufted pile fabrics with a backing, the steps of laterally tensioning the backing, enveloping the marginal edges of said backing with folded tapes, disposing the folded edges of the tapes in spaced parallel relation, arranging a series of parallel longitudinal pile yarns on said backing and tapes parallel to said folded edges, and projecting simultaneously portions of each pile yarn through the fabric to form transverse rows of tufts extending across its entire width including said folded tapes to secure the latter in place.

5. A tufted pile fabric composing a first ply of backing material having side edges, a second ply of backing material folded over and embracing each of said side edges of the first ply to form at least triple ply marginal portions, the outermost folds of said second plies being

straight and constituting the outermost side edges of the pile fabric, a series of pile yarns each lying in parallel relation to said outermost side edges of the fabric against the first ply of backing and extending therethrough at spaced intervals along its length to form pile projections, selected pile yarns of said series projecting through said triple ply portions.

6. A method of making a pile fabric, which comprises the steps of continuously advancing a ply of backing material having side edges in the direction of its length, continuously advancing a second ply of backing material having a straight outer edge and disposing said second ply overlying each edge of said first ply to form at least a double ply marginal portion adjacent each side of the backing, while maintaining the straight outer edges of said second plies of backing material parallel to each other and to the line of advance of said plies, and passing a selected number of pile yarns at intervals simultaneously through said plies of backing to form pile elements projecting in a like number of longitudinal rows parallel to said line of advance, the yarns forming the pile elements in the rows adjacent the lateral edges of the backing passing through both plies thereof.
